UNITED STATES PATENT OFFICE.

JOHN F. PRIBNOW, OF MELLEN, WISCONSIN.

EMERY-WHEEL BENCH-GRINDER.

1,081,465.

Specification of Letters Patent. Patented Dec. 16, 1913.

Application filed October 21, 1912. Serial No. 726,902.

To all whom it may concern:

Be it known that I, JOHN F. PRIBNOW, a citizen of the United States, residing at Mellen, in the county of Ashland and State 5 of Wisconsin, have invented a new and useful Emery-Wheel Bench-Grinder, of which the following is a specification.

It is the fundamental object of my invention to provide a grinder in which the abrasive wheel, such as an emery wheel, may be mounted on its shaft or arbor and removed therefrom without requiring any special tools, and when mounted on the shaft will always run true regardless of how often it 15 has been removed.

It is my further object to provide a protective hood which can be adjusted to provide for the wearing down of the abrasive wheel and to accommodate varieties of work, 20 and may be swung back to allow the ready removal or replacement of the wheel.

Further objects will appear hereinafter.

The accompanying drawings illustrate my invention.

25 Figure 1 is a front elevation of a grinder embodying my invention; Fig. 2 a plan view of the grinder shown in Fig. 1; Fig. 3 a section on line 3—3 of Fig. 1; Fig. 4 an enlarged detail, partly in section, showing the 30 mounting of the abrasive wheel on the shaft or arbor; Fig. 5 an enlarged section on line 5—5 of Fig. 3; Fig. 6 a perspective view of the releasing and tightening pawl; Fig. 7 a detail of the pawl spring; Fig. 8 a front 35 elevation of the driving pulley, showing the lugs for coöperating with the pawl; Fig. 9 a section on the line 9—9 of Fig. 8; Fig. 10 a cross section through one of the bearings, taken on the line 10—10 of Fig. 11; Fig. 11 40 a section on line 11—11 of Fig. 10; Fig. 12 a partial plan view showing the mounting of the protective hood; and Fig. 13 a detail of the supporting bolt on which the protective hood is mounted.

45 The shaft or arbor 10 is rotatably mounted in bearings 11 on a suitable frame 12, the bearing caps 13 being provided with clamping screws 14 and spacing screws 15 whereby they may be accurately adjusted to the shaft 50 10. On each projecting end of the shaft 10 an abrasive wheel 20 may be removably mounted. In order to insure trueness in these abrasive wheels, no matter how often they are removed and replaced, each such wheel is mounted on a metal sleeve 21 provided with a flange 22 between which and

a clamping plate 23 screwed on to the end of the sleeve 21 the wheel 20 is permanently clamped, being held between the flange 22 and the clamping plate 23 until it is worn out and ready to be discarded. The sleeve 21 is screw-threaded internally to coöperate with an external screw thread 24 on the end of the shaft 10, which is provided near each end with a shoulder 25 against which the sleeve 21 abuts when it is screwed on to the end of the shaft.

Between the two bearings 11 is mounted the driving means for the shaft 10. In the arrangement illustrated this comprises a 70 pulley 30 fixedly mounted on such shaft, as by a Woodruff key 31. The pulley is conveniently provided at one end with an extension 33, a loose collar 34 being fastened to the shaft near the other end of the pulley 75 by a set screw 32 and providing a convenient means for taking up the end play of the shaft. This extension 33 and the collar 34 project over the adjacent ends of the bearings 11 and bearing caps 13 and serve as 80 dust-proof coverings therefor. Each sleeve 21 may have a similar projection 35 to protect the adjacent end of the bearing 11. The extension 33 of the pulley 30 is cut away as shown in Fig. 9 to form one or more radially 85 projecting lugs 36. An arm or pawl 37 is pivoted on a pin 38 extending into one of the pedestals for a bearing 11, a spring 39 surrounding the pin 38 and being seated within a pocket 40 on the arm 37 to keep 90 the latter from accidental movement and from rattling. The arm 37 has a projection 41 in the same plane as the lugs 36. By raising the arm 37, projection 41 is swung into the circle in which the lugs 36 rotate, so 95 that it engages such lugs in their rotation. By thus raising the arm 37 and turning the wheel 20 by hand in the desired direction, the lug 41 engages a lug 36 and suddenly arrests the movement of the shaft 10, while 100 the momentum of the wheel 20 jars it firmly against or from the shoulder 25 and thus into or out of place. This provides for mounting and dismounting the abrasive wheel without the use of special tools. 105

For safety purposes, a protective hood 45 is provided for each emery wheel. The hood 45 is pivotally mounted on a bolt 46 which extends through a slot 47 in a projection 48 from the back of the adjacent bearing 110 pedestal, and is provided with a lateral lug 49 through which a screw 50 extends so that

it may rest on the top of the projection 48. By loosening the bolt 46 the hood may be swung from over the abrasive wheel 20 to allow the latter to be removed or replaced, the slot 47 also providing for adjusting the distance of the front end of the hood from the surface of the abrasive wheel to accommodate different kinds of work and to compensate for the wearing away of the abrasive wheel. By means of the screw 50, the width of the opening through which the work is applied to the wheel, may be adjusted. Each bearing pedestal may also have a forward projection 55, which is vertically slotted to receive a clamping bolt 56 for holding the longitudinally slotted work table 57. The nut coöperating with each bolt 56 preferably has a hexagonal part 58 for the reception of a wrench and a thumb screw part 59 for hand manipulation. The work table 57 preferably has an extension along the side of the abrasive wheel, which extension may take the form of an integral part 60 as shown at the left of Fig. 2 or of a sliding table 61 slidably mounted on a T end 62 of the work table 57. The sliding table 61 may be provided with a cross slide 63 on which is mounted a protractor 64 carrying a guide 65 for holding the work at any desired angle relative to the side of the wheel 20.

I claim as my invention:

1. A grinding device, comprising an abrasive wheel, an internally threaded sleeve on which said wheel is permanently mounted, a threaded shaft upon which said sleeve may be removably mounted, said

sleeve and said shaft being provided with engaging shoulders for locking the two together against accidental displacement, a projecting lug carried by said shaft, and a movable pawl which may be moved into and out of the path of movement of said lug to coöperate therewith to produce a sudden stoppage of the shaft. 40

2. A grinding device, comprising an abrasive wheel, a flanged sleeve extending through said wheel with the flange bearing against the side thereof, and a clamping plate screw-mounted on said sleeve and bearing against the other side of said wheel to clamp the latter between it and the flange on the sleeve, said sleeve being internally screw-threaded and provided with a shoulder, in combination with a screw-threaded shaft upon which said sleeve may be threaded, said shaft being provided with a shoulder for coöperating with the shoulder on the sleeve to lock the sleeve and shaft together, a projecting lug carried by said shaft, and a movable pawl which may be moved into and out of the path of movement of said lug to coöperate therewith to produce a sudden stoppage of the shaft to force said two shoulders together or apart by the momentum of the sleeve and wheel. 45

In witness whereof, I, have hereunto set my hand and seal at Mellen, Wisconsin, this 12th day of October, A. D. one thousand nine hundred and twelve.

JOHN F. PRIBNOW. [L. S.]

Witnesses:

M. J. DONAHUE,
EARL C. POUNDSTONE.
